United States Patent

Des. 234,360
Patented Feb. 18, 1975

234,360

TEACHING MACHINE

Ernest R. Duncan, Harmony Hill, Mount Harmony Road,
Bernardsville, N.J. 07924

Filed June 8, 1973, Ser. No. 368,267

Term of patent 14 years

Int. Cl. D14—01

U.S. Cl. D25—1 R

FIG. 1

FIG. 2

FIG. 3

FIG. 4

FIG. 5

FIG. 6

FIG. 1 is a top plan view of a teaching machine showing my new design.

FIG. 2 is a bottom plan view thereof.

FIG. 3 is a rear elevational view thereof, shown in an inverted position.

FIG. 4 is a front elevational view thereof.

FIG. 5 is a left-side elevational view thereof, shown in an upright position.

FIG. 6 is a right-side elevational view thereof, shown in an upright position.

I claim:

The ornamental design for a teaching machine, as shown and described.
